CLAIM

The ornamental design for a motorcycle radio housing, as shown and described.

DESCRIPTION

FIG. 1 is a perspective view of the motorcycle radio housing of the present invention;

FIG. 2 is a top view of the motorcycle radio housing;

FIG. 3 is a front view of the motorcycle radio housing;

FIG. 4 is a bottom view of the motorcycle radio housing;

FIG. 5 is a side view of the motorcycle radio housing;

FIG. 6 is a back view of the motorcycle radio housing; and,

FIG. 7 is a second perspective view of the motorcycle radio housing shown in position of use on a motorcycle, which is shown in broken lines for illustrative purposes only and forms no part of the claimed design.
